UNITED STATES PATENT OFFICE.

JAMES HOWLETT, OF JERSEY CITY, AND EDWARD J. BROOKS, OF EAST ORANGE, N. J., ASSIGNORS TO E. J. BROOKS & CO., OF NEW YORK, N. Y.

SHACKLE WIRE AND CORD FOR SEALS.

SPECIFICATION forming part of Letters Patent No. 249,357, dated November 8, 1881.

Application filed October 20, 1880. (Model.)

To all whom it may concern:

Be it known that we, JAMES HOWLETT and EDWARD J. BROOKS, citizens of the United States, residing, respectively, at Jersey City and at East Orange, in the State of New Jersey, have jointly invented a new and useful Improvement in Shackle Wires and Cords for Seals, of which the following is a specification.

This invention relates to the manufacture and use of seals for securing railway freight-cars, baggage, packages of valuable merchandise, &c., against the entrance of unauthorized persons; and the particular class of such seals to which our invention relates is those seals which consist of flexible shackles of wire or cord adapted to be readily passed through staples or the like, and seal-disks, usually of lead, having apertures to receive the ends of the shackles, which are secured therein in the act of impressing the seal-disks with their distinguishing marks.

The requisite most important in seals of this description is security against "stripping"—that is to say, against the withdrawal of an end of the shackle from a pressed seal-disk without such injury to either as will insure detection. Another requisite is shackles of sufficient endurance to be reasonably free from liability to be broken accidentally or by mischievous boys, and, owing to the competition of trade, another requisite is the utmost cheapness, which demands an article capable of rapid production by automatic machinery. Among the qualities desirable, but not absolutely requisite, are facility of manipulation, demanding shackle ends which will enter the seal-disks readily, and in the case of cording-shackles the preservation of the customary size and general characteristics.

The object of our invention is to furnish shackle wire and cord for seals possessing all the aforesaid requisites and desirable qualities, when used in combination with ordinary plain lead seal-disks properly pressed, and adapted at the same time for use in connection with safety seal-disks of the most approved forms for protection against insecurity from inadequate pressing.

Our invention consists, first, in a novel combination of features in a shackle wire or cord, whereby a continuous succession of highly effi-

cient holding-surfaces may be formed in the process of its manufacture by automatic machinery; secondly, in a novel combination of features, whereby a peripheral holding-strand is received and held with superior facility and efficiency, and the wire or cord is adapted to be made of any desired strength and size; and, thirdly, in a species of our genus of products combining all the aforesaid features or characteristics, as hereinafter more fully set forth.

In the accompanying drawings, which form part of this specification, Figure 1 is a perspective view of a shackle-wire and seal-disk illustrating this invention, the same being shown as ready for use. Fig. 2 is a view of the same as in use, the pressed seal-disk being shown in section. Fig. 3 is an elevation of a piece of the shackle-wire on a larger scale, and Fig. 3^x represents a cross-section thereof at the line x x , Fig. 3. Figs. 4 and 5 are elevations of pieces of shackle-wire illustrating modifications; and Figs. 6, 7, 8, and 9 are like illustrations of shackles, made in part of hemp, representing additional modifications. Fig. 10 is a face view of three other seal-disks such as we propose to use.

Like letters of reference indicate corresponding parts in the several figures.

The shackle-wire S, Figs. 1 to 3^x, inclusive, consists of a loosely-twisted wire body, b , of two strands, and a peripheral holding-strand, c , composed of two wires twisted together and wormed upon said body in the form of an open spiral coil. Said holding-strand thus formed presents a continuous succession of efficient holding-surfaces throughout its length, the respective wires which compose the strand assuming positions more or less nearly at right angles to the body b , at parts as shown in Fig. 3, while the thin individual wires at their outermost points constitute what we term "thorns," serving as sharp entering points for the strand as a whole. Moreover, the twisted strand is very materially larger in diameter, and consequently more prominent upon the body b , than a single strand of the same weight. The twisted body b serves not only to resist longitudinal strain, to receive the holding-strand c , and to render the shackle-wire as a whole of the desired diameter, but its spiral creases provide for applying said holding-strand to the

body by "worming" the latter therewith simultaneously with the operation of twisting the body, and the successive coils of the holding-strand are thereby held against displacement. 5 The holding-strand may also be twisted at the same operation, and it may consist of more than two wires, as may also the body *b*, if desired; or the relative sizes of the respective wires may be varied without departing from 10 our invention. Increasing the number of the wires in the body with a given twist and diameter renders the wormed holding-strand more open as regards its coils. Increasing the number of wires in the holding-strand is not ad- 15 vantageous. A loosely-twisted strand of two wires possesses the advantages above named in the highest degree. The sizes of the wires chiefly determine the diameter of the product.

The illustrative shackle *S*², Fig. 4, is composed of a tightly-twisted wire body, *b*², of two strands, and a twisted holding-strand, *c*², of two wires, the latter applied without reference to worming, being made stiff enough to preserve its shape. *S*³, Fig. 5, has a similar holding-strand, *c*³, on a single-wire body, *b*³. *S*⁴, Fig. 6, has a two-strand twisted body, *b*⁴, of hemp, wormed with a holding-strand, *c*⁴, of tightly-twisted and sized hemp, inclosing a wire, *d*, which preserves its shape. A holding- 20 strand of single wire may be used in like manner. *S*⁵, Fig. 7, has a body, *b*⁵, of hemp, inclosing a double-twist core-wire, *a*, in connection with a double-twist wire holding-strand, *c*⁵. *S*⁶, Fig. 8, has a two-strand twisted body, *b*⁶, 25 of hemp alone, wormed with a double-twist wire holding-strand, *c*⁶; and *S*⁷, Fig. 9, has a two-strand twisted body, *b*⁷, of hemp alone, carrying a holding-strand, *c*⁷, composed of hemp and fine wire twisted together.

40 Other modifications, together with such adaptations of existing machinery as may be required to produce any given style or size, will suggest themselves to those skilled in the manufacture of cable wire and cord.

45 Our improved shackle-wire is readily made small enough, of the description shown at *S*, for use with the smallest seal-disks. This is illustrated by Fig. 1, *D* representing the smallest seal-disk used by E. J. Brooks & Co. as a 50 part of their tag-seal patented October 15, 1878;

h its crossed threading-holes, and *r* its rivet-stud.

In using the improved shackle, one of its ends, *e*, is passed through a pair of staples, *s*⁸, for example, and its two ends are then inserted in 55 the holes of the seal-disk, which they enter readily, being of uniform size throughout as regards outer diameter. The seal-disk is next pressed, causing the lead to enter between the coils of the holding-strand, and between its 60 individual wires when the double-twist wire strand is used, as indicated in Fig. 2, securely holding the shackle ends in place.

As crossed in the safety seal-disk *D*, or in *D*², Fig. 10, which represents another form of 65 the same patented by E. J. Brooks, March 30, 1875, or as crossed by locking-pieces in the safety seal-disk *D*³, patented by E. J. Brooks, September 1, 1874, the ends of our improved shackles interlock with each other or with locking-pieces in the most effective manner; but, if properly pressed, a plain seal-disk, *D*⁴, Fig. 10, is amply safe in connection with said improved shackles, which are primarily intended 70 for use therewith.

75 The following is what we claim as new and of our joint invention, and desire to secure by Letters Patent, namely:

1. A shackle-wire or cord for seals, consisting of two parts—a body and a holding-strand—80 one of which parts is composed of strands twisted together, the said holding-strand being coiled around said body, substantially as herein described.

2. In a shackle-wire or cord for seals, the 85 combination, with a body of any description, of a superposed holding-strand composed of wires twisted together and coiled around said body, substantially as herein described, for the purpose set forth.

3. As a new article of manufacture, shackle-wire having a body composed of strands twisted together and wormed with a peripheral holding-strand composed of wires twisted together, substantially as herein specified.

JAMES HOWLETT.
EDWARD J. BROOKS.
